UNITED STATES PATENT OFFICE.

SIMON W. WARDWELL, OF PROVIDENCE, RHODE ISLAND; CARL V. J. CHRISTENSEN, EDWIN C. SMITH, ARTHUR A. ARMINGTON, AND WILLARD W. BARDSLEY, EXECUTORS OF SAID SIMON W. WARDWELL, DECEASED.

FOLDING STAND, STOOL, OR OTHER LIKE ARTICLE.

1,394,381.

Specification of Letters Patent.

Patented Oct. 18, 1921.

Application filed January 17, 1919. Serial No. 271,699.

To all whom it may concern:

Be it known that I, SIMON W. WARDWELL, a citizen of the United States, residing at Providence, in the county of Providence, 5 State of Rhode Island, have invented certain new and useful Improvements in Folding Stands, Stools, or other like Articles, of which the following is a specification.

My invention relates to improvements in 10 folding stands, tables, stools or other like articles of domestic and commercial utility. The particular object of my improvement is to provide an article of this type which while being light in weight will have sufficient strength and rigidity to support relatively heavy loads, and which may be folded into small compass to render it easily portable. Other objects of the improvement 15 are to simplify the construction of the device, while rendering it more convenient and easy to operate in setting it up or folding its parts together, and further, to enhance its artistic appearance.

The manner and means for carrying out 20 these improvements are fully described in the following specification, illustrated by the accompanying drawings, in which like reference characters designate like parts. In the drawings:

30 Figure 1 is a side elevation of the improved stand or table, showing it erected; Fig. 2, a front elevation of the same;

Fig. 3, a side view of the device, showing its parts in folded relation;

35 Fig. 4, a vertical sectional view of one of the upper hinge-joints of the device;

Fig. 5, a rear view of the same, showing the detent-catch for the joint; and

40 Figs. 6 and 7, views similar to Figs. 4 and 5 illustrating one of the lower joints of the device.

Referring first to Figs. 1 and 2, my improved stand or table as here shown comprises an upper section A hingedly mounted 45 on a central, main section B which is supported from the floor by folding legs C, C'. The upper section A consists of two parallel side-arms or uprights 2, 2 surmounted by a flat top or table T. Preferably, the uprights 50 2, 2 are of skeleton structure, having portions cut away to lighten their weight, and with their outlines conforming to graceful scrolls as shown in Fig. 1. At their upper ends the uprights 2, 2 are formed with hol-

low blocks 3, 3 joined by a cross-tie 4 and 55 surmounted by square lugs 5, 5. The tabletop T may be constructed as a casting, or may be struck up from sheet-metal, and is formed on its sides with an overhanging, flanged rim 6. As shown in Fig. 2, the top 60 T rests on the lugs 5, 5 of the uprights 2, 2 with its flange 6 overhanging the sides thereof and riveted or otherwise secured thereto at 7, 7, see also Fig. 1.

At their lower ends the uprights 2, 2 are 65 formed with hubs 8, see Fig. 4, which are surrounded by circular rims 9 joined thereto by radial spokes 10. The rims 9 provide extended, ring-like bearing-seats which are adapted to abut corresponding circular seats 70 11 at the top of the side-members or uprights 12, 12 of the central stand section B. As shown in Fig. 1, the uprights 12 of the section B are also of skeleton structure, being ornamented by grill-work in scroll design. The bearing-seats 11 on the upright 75 12 are formed with central hubs 13 connected thereto by spokes 14, see Fig. 4, and both hubs 8 and 13 at either side of the stand are bored axially to receive a tubular 80 bushing 15 which serves as the pivot for the hinged joint between the parts. As shown in Fig. 4, the bushing 15 is provided with outwardly turned flanges 16 and 17 formed by spinning or swaging up the 85 ends of the tube. The inner flange 16 abuts the end of the hub 8 on the upright 2, while the outer flange 17 is spaced away from the end of the hub 13 on the upright 12 to adapt the bushing to receive a spider-like 90 spring-washer 18. The washer 18 is preferably constructed of sheet-metal with a central bore fitted to the bushing 15, and with radial arms 19, dished inwardly to adapt them to bear against the bearing-ring 11 to 95 force it against the seat 9, see also Fig. 1. It will be understood that the bushing 15 is inserted through the hubs 8 and 13 and the spring-washer 18 placed on its outer end before the flange 17 is swaged out therefrom. After the parts are thus assembled the swaging out of the flange 17 draws the parts together to force the spring-washer 18 against the bearing-ring 11, whereby the latter is held against the ring-seat 9 to provide a frictional contact therebetween. In this manner the parts are maintained in co-operative relation without play or backlash

100

105

while providing a slight resistance to the turning movement of the hinge.

Inserted through the bore of the bushing 15 is a pin or stud 20 formed with a head 21 which abuts the outer flange 17 of the bushing. The stud 20 projects beyond the inner end of the bushing 15 to enter a bore 26 in the end of one of the arms of a lateral frame or cross-brace 24 which joins the two uprights 12, 12 together, see Fig. 2. The frame 24 is of skeleton structure in the form of an ornamental cross bearing a central panel 25. The panel 25 may be ornamented with a design in relief or may serve as a name-plate for commercial legends or other inscriptions. Extending between the upper arms of the frame 24 is a hollow rod or tubular cross-tie 22 having its extremities fitted over the ends of the opposite studs 20. As shown in Fig. 4, the ends of the cross-tie 22 abut the sides of the upper arms of the frame 24 and are united to the studs 20 by rolling the walls of the tubing into annular grooves 23 formed on the peripheries of the studs. At the ends of the lower arms of the frame 24 are hubs 27 having bores for receiving headed studs 28 driven therethrough. The ends of the studs 28 project beyond the hubs 27 and are inserted in the bores of bushings 32 which unite the side-members 12 of the stand-section B with its legs C, C', see Fig. 6.

Referring to Figs. 1 and 6, the grill-work of the side-members or standards 12 terminates at the lower end in enlarged, circular rims or bearing-rings 30 provided with integral spokes supporting central hubs 31. Inserted through the axial bores of the hubs 31 are the tubular bushings 32 which serve as pivots for the hinge-joints of the legs C, C'. Both legs C, C' on each side of the stand are formed with circular bearing-rings 33, 34 united to central hubs 35, 36 by radial spokes 37, 38. As shown in Fig. 6, the bearing-ring 30 of the standard 12 abuts the side of the ring 33 on one leg C and the outer face of the latter fits against the ring 34 on the other leg C', providing a three-part complementary bearing which is held together by the flanged ends of the bushing 32 reaching through the hubs 31, 35, 36. The flanges 39 and 40 on the ends of the bushing 32 are swaged outwardly against the ends of the hubs to draw the parts snugly together, but in this case no spring-washer is employed as with the upper joints before described. As shown in Fig. 1, the legs C of the front pair curve outwardly at the bottom to form extended feet 41, while the legs C' of the other pair are designed with reverse curves terminating in the smaller feet 42. Extending between the opposite legs C, C and C', C' of each pair are brace-rods 43, 44 which are riveted or otherwise secured at 65 their ends in suitable bosses 45.

The several parts of the stand are held in erected position by means of spring-controlled detents operating on the hinge-joints. As shown in Figs. 1 and 5, a lever 50 is pivoted on each upright 2 of the upper stand-section A to adapt it to lock the latter in extended relation with the uprights 12 of the section B. Preferably, the lever 50 is constructed of sheet-metal, being formed with opposite, parallel arms 51 bent inwardly to straddle the sides of the upright 2, and pivoted thereto by a cross-pin 52. At its lower end the lever 50 is bent at right-angles to form a toe 53 which is offset from the side of the upright 2 to adapt it to engage a slot 54 cut into the edge of a fin 55 on the upright 12. A flat spring 56 riveted to the inner side of the lever 50, see Fig. 5, bears at its opposite end on the edge of the upright 2 to maintain the toe 53 of the lever 50 in engagement with the slot 54.

A similar arrangement of detents is applied to the joints between the side-members 12 and the legs C, C'. Referring to Figs. 1 and 7, the leg C' carries a lever 60 having arms 61 straddling its sides and pivoted on a cross-pin 62. The upper end of the lever 60 is offset laterally to adapt it to lie across the joint between the bearing-rings 33, 30 of the leg C and upright 12, and is formed with a toe 63 which engages alining notches or slots 64 and 65 therein. On the upper side of the slots 64, 65 are projecting lugs 66, 67 which act as stops for the end of the lever to insure that its toe 63 will drop into the slots after they are brought into alinement by turning the parts of the joint. A spring 68 on the under side of the lever 60 bears against the edge of the leg C' to carry the toe 63 of the lever into the slots 64, 65 as they are brought into register therewith. Having now described the construction and arrangement of the parts of my improved stand or table, the manner of erecting and folding it will next be explained.

Figs. 1 and 2 illustrates the stand erected with the opposite pairs of legs C, C' spread apart to provide a firm support on the floor, and with their bearing-rings 33 and 34 locked to the rings 30 of the uprights 12 by the levers 60 engaging the slots 64, 65, see Fig. 7. The legs C, C' are thus held from turning on their hinges and the uprights 12 are supported in vertical position thereon, and in rigid relation thereto. In the same manner the upper section A of the stand is held erect on the mid-section B with the bearings 9 and 11 locked against turning through the engagement of the levers 50 with the slots 54. With the table in its erected position the uprights 2 and 12 are tied together and braced at the top by the cross-rod 22, while the frame 24 extending between the several joints of the parts stiffens and reinforces the mid-section B by bracing the upper and 130

lower ends of the uprights 12 against lateral movement. To further stiffen and brace the stand the cross-rod 43 and 44 tie the opposite pairs of legs C, C' together to prevent them from spreading. It will thus be seen that the sides of the stand are rigidly trussed and braced against lateral movement so that its whole structure is reinforced and stiffened to provide the required 10 stability and prevent wobbling.

The most convenient method of folding the stand for storing or carrying is as follows: The operator stands at the front and reaching in back of the uprights 2 presses 15 on the levers 50 to release their ends from the slots 54 on the uprights 12. The upper section A is then turned on its hinges to fold it down against the central brace or frame 24, as represented by dotted lines in 20 Fig. 1. With the top section A folded down in this manner the operator next grasps the uprights 12 near their lower bearings and turns the stand bodily over to rest its back on the floor. Now by reaching in under the 25 sides of the stand, a slight pressure of the fingers on the levers 60 will unlock the legs C, C' and they may be folded back as shown in Fig. 3. The rear legs C' C' are first brought around until their tie-rod 44 strikes 30 against the back of the legs C, C and both pairs of legs can then be swung together to fold them down alongside the uprights 12, 12. Referring to Fig. 3, as the legs are carried into this position the tie-rods 43, 44 35 will bring up against the curved sides of the uprights 2, 2 of the upper folded section A, and in this way a limit or stop is provided to maintain the parts in their folded relation. It will be observed from Fig. 3 that 40 the stand may thus be folded into a very compact form to occupy a minimum space. In its folded relation it may be inclosed in a small hand-valise or traveling-case or may be stored within a limited space.

45 My improved device may be constructed in the form of a table, stand or desk as herein illustrated, or may be adapted for other purposes. For instance, it may be used as a stool or chair by providing a seat 50 for its top, or it might be made in the form of a settee, bench or other article of furniture. In the form shown it provides a convenient support for household articles such as phonographs, or for office appliances 55 such as typewriters and the like. It will be noted that while being extremely light in weight and ornamental in appearance, the device is nevertheless exceedingly staunch and rigid and will support relatively heavy 60 loads. Furthermore, it is easily set up and when once erected cannot collapse, while requiring but a few simple operations to fold its parts together. In its folded relation it is extremely compact and is therefore 65 well adapted for transportation or storage.

Various modifications might be made in the structure and arrangement of the parts of my improved device without departing from the spirit or scope of the invention, therefore, without limiting myself to the exact embodiment herein shown and described, what I claim is:

1. In a folding stand, stool or like article of utility, the combination with a main central section comprising uprights, of a cross-frame connected to the upper and lower ends of the uprights, an upper section having uprights hinged to those of the central section, legs hinged to the lower ends of the central section, and detent-means on the 70 hinges preventing turning action thereof to maintain the parts of the stand in extended relation.

2. In a folding stand, stool or like article of utility, the combination with a central 85 section comprising opposite parallel uprights formed with hinge-joints at their upper and lower ends, of an upper section comprising parallel uprights hinged to the joints of the central section and joined together by a top, folding legs hinged to the lower joints of the central section, and a cross-frame connected to the four joints of the central section to brace its sides.

3. In a folding stand, stool or like article 95 of utility, the combination with a central section comprising opposite parallel uprights formed with enlarged bearing-seats at their upper and lower ends, of an upper section comprising parallel uprights 100 formed with bearing-seats at their lower ends fitted to the bearings on the central section, a top connecting the upper ends of the uprights of the upper section, two pairs of legs having bearing-seats fitted to the 105 seats at the lower end of the central section, pivots connecting the several bearings of the parts to provide hinge-joints therebetween, and detent-means on the hinge-joints to prevent relative turning of the 110 bearings whereby to lock the parts in extended relation.

4. In a folding stand or like article of utility, the combination with a central section comprising opposite parallel uprights 115 formed with bearings at their upper and lower ends, of an upper section comprising uprights having bearings at their lower ends, pivots connecting said bearings, a top supported on the upper ends of the last-named uprights, folding legs pivoted to the bearings at the lower end of the central uprights, and a lateral frame extending between the sides of the central section with its ends abutting the inner sides of the 120 several bearings.

5. In a folding stand or the like, the combination with a central section comprising opposite parallel uprights provided with pivot bearings at their ends, of an upper 130

section having uprights pivoted to the upper bearings of the central section, two pairs of legs pivoted to the lower bearings of the central section, and detent levers mounted on said bearings and adapted to engage alining cross-slots in the opposite sides thereof to lock the parts in extended relation.

6. In a folding stand or the like, the combination with a central section comprising opposite spaced uprights formed with pivot bearings at their ends, of an upper section comprising uprights hinged to the upper bearings of the central section, a cross-rod extending between said bearings, a cross-frame extending between the sides of the central section, two pairs of legs pivoted to the lower bearings of the central section, and detent-means for locking the bearings from turning whereby to hold the parts in extended relation.

7. In a folding stand or the like, the combination with a central section comprising opposite parallel uprights provided with bearings at their upper and lower ends, of an upper section having uprights provided with bearings fitted to those at the top of the central section, a pair of folding legs having bearings fitted to those at the bottom of the central section, bushings inserted through the bearings and held therein by flanges at their ends, a lateral frame extending between the bearings on the uprights of the central section, and studs inserted in the bushings of the bearings to secure the frame in place.

8. In a folding stand or the like, the combination with a central section comprising opposite parallel uprights formed with bearings at their ends, of an upper section having opposite uprights formed with bearings fitted to those at the top of the central section, folding legs formed with bearings

fitted to those at the bottom of the central section, bushings extending through the bearings and flanged outwardly at their ends to hold the parts in place, a lateral frame extending across the central section between its bearings, studs inserted in the bushings of the bearings to hold the frame in place, and a cross-tie extending between the ends of two opposite studs to brace the uprights apart.

9. In a folding stand, the combination with a central section comprising two opposite uprights formed with bearings at their ends, of an upper section having uprights provided with bearings fitted to those at the top of the central section, folding legs having bearings fitted to those at the bottom of the central section, bushings extending through said bearings, a lateral frame extending between the bearings, studs inserted through the bushings to secure the frame in place, and a tubular cross-tie extending between two opposite studs and united thereto by rolling its walls into peripheral grooves in the studs.

10. In a folding stand or the like, the combination with a central section comprising opposite parallel uprights, of a cross-frame connected to the upper and lower ends of said uprights, an upper section comprising a top supported on uprights hinged to the upper ends of the central uprights to adapt it to fold down therebetween, legs hinged to the lower ends of the central uprights to adapt them to fold upwardly alongside thereof, detent-means on the hinges to lock the parts in extended relation, and means to limit the movement of the parts as they are folded together.

In testimony whereof I affix my signature.

SIMON W. WARDWELL.
